UNITED STATES PATENT OFFICE.

LAFAYETTE M. PETTIT, OF CRIPPLECREEK, COLORADO.

SLIDE-VALVE MECHANISM.

SPECIFICATION forming part of Letters Patent No. 795,165, dated July 18, 1905.

Application filed March 4, 1904. Serial No. 196,616.

To all whom it may concern:

Be it known that I, LAFAYETTE M. PETTIT, a citizen of the United States of America, residing at Cripplecreek, in the county of Teller and State of Colorado, have invented certain new and useful Improvements in Slide-Valve Mechanism; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 My invention relates to improvements in slide-valve mechanism for steam-engines, my object being to provide a construction of this class in which the clearance or the space between the piston and the valve when the 20 piston is at its limit of movement in either direction shall be reduced to a minimum. This is an important feature in slide-valve mechanism, since the less the volume of steam required to fill the clearance-space the 25 quicker will the steam-pressure in this space act upon the piston of the cylinder with the full boiler-pressure. Instead of having long passages extending from the extremities of the cylinder to the steam-chest I provide vertical 30 passages or ports leading from the extremities of the cylinder to the steam-chest, and instead of having the cylinder reinforced to form a flat seat where the slide-valve is located the surface of the valve is formed 35 arc-shaped to conform to the curve of the cylinder, whereby the ports leading from the cylinder to the steam-chest are only of a depth equal to the thickness of the wall of the cylinder. In this way it is understood 40 that the length of the ports is much less than where the top of the cylinder is reinforced to form a flat base or platform for the slide-valve.

Another feature of my improvement is that 45 my improved valve is perfectly balanced.

Having briefly outlined my improved construction, as well as some of the functions it is intended to perform, I will proceed to describe the same in detail, reference being

made to the accompanying drawings, in which 50 is illustrated an embodiment thereof.

In the drawings, Figure 1 is a vertical longitudinal section taken through my improved slide-valve mechanism and extending into the cylinder. Fig. 2 is a similar view showing 55 the valve in a different position. Fig. 3 is a cross-section taken through the steam-chest at one end and cutting the cylinder. Fig. 4 is a horizontal section of the same. Fig. 5 is a perspective view of the valve, shown in detail. Fig. 6 is a top view of the steam-chest with the top plate removed. Fig. 7 is a section taken through the packing-groove of one of the 60 slide-valve heads. Fig. 8 is a detail perspective view of the packing construction.

The same reference characters indicate the 65 same parts in all the views.

Let A designate the steam-chest, whose side walls A' extend upwardly from the cylinder, the steam-chest being closed by a top plate 70 A². The bottom of the steam-chest is curved to conform to the curve of the cylinder, and the wall of the latter is provided with a vertical port A³, located at each end thereof. The slide-valve B is composed of two heads 75 B', connected by a bar B². The live-steam space is between the heads of this valve, while the steam-chest is provided with an exhaust-port A⁴, located at each end thereof. The heads of the valve are curved to conform 80 to the curve of the cylinder except at their outer extremities beyond the ports A³, where the bottom of the steam-chest is composed of narrow ledges A⁵, these ledges being of sufficient length to form a support 85 for the heads of the valve during the longitudinal movement of the latter. At each end of each head of the valve the latter is provided with lugs B³, which project inwardly. The function of these lugs is to balance the 90 valve while it is passing the steam-ports. If it were not for these lugs or projections, the upward pressure of the steam, whether live or exhaust, on the valve-head while crossing the steam-port would throw the valve out of 95 balance, and thus cause increased resistance to its movement in the steam-chest. The lugs or projections B³, however, project into the

steam-chest while the valves are crossing the ports, and the downward pressure of the live steam on these lugs or projections neutralizes the effect of the upward steam-pressure on the 5 valve-heads while crossing the ports. The area of the parts B³ is so regulated as to produce this result. It will therefore be understood that the parts B³ may be made of any suitable size in order to perform the required function.
10 The bottom of the steam-chest is cut away between the seats B⁴, as shown at B⁵, so that as soon as a valve-head has passed beyond the steam-port into the steam-chest or the space containing the live steam the parts B³, connected with the valve-head, will project over the reduced part B⁵ of the bottom of the valve-chest and allow the live steam to pass below the said projections, thus neutralizing the effect of these projections after they have 15 performed their function. Each valve-head is grooved to receive packing rings or plates B⁶, which interlock and overlap each other in such a manner as to make perfectly steam-tight joints. The heads B' of the valve are 20 of rectangular shape except their bottoms or lower extremities, which are arc-shaped to conform to the curve of the top of the cylinder or bottom of the steam-chest upon which the valve slides. As shown in the drawings, 25 one head of the steam-chest is provided with separated lugs B⁸, having inwardly-turned outer extremities B⁹. The eccentric-rod C is provided with a T-shaped head C', adapted to enter or pass between the lugs B⁸ from 30 above, after which the eccentric-rod and the valve are connected in operative relation. The rod may of course be detached from the valve-head by simply lifting it out of place in a manner that will be readily understood.
35 40 In the drawings the cylinder is designated D, the cylinder-heads D', and the piston of the cylinder D².

From the foregoing description it is believed that the use and operation of my improved 45 slide-valve will be readily understood. In Fig. 1 of the drawings the slide-valve is shown moved toward the right far enough to uncover the ports E and E'. In this case the port E is a live-steam port, through which the live 50 steam passes from the steam-chest A between the valves to the right-hand end of the cylinder D and to engagement with the piston D², while the port E' becomes an exhaust-port, since the steam at the left of the cylinder is 55 passing out of the latter through the port E' into one end of the steam-chest at the left of

the slide-valve head and out of a port A⁴. In the construction shown in Fig. 2 the port E is closed against the live steam, while the port E' is still partly open to the exhaust, and 60 the piston under this arrangement must complete its stroke toward the left by expansion. In this case the steam in the cylinder at the right of the piston will act on the right-hand valve-head B' with a tendency to force 65 the latter upwardly; but the downward pressure of the live steam in the steam-chest on the parts B³ of this valve-head neutralizes the upward pressure of the steam in the cylinder, whereby a perfect balance of the valve is 70 maintained, while as soon as the right-hand piston B' is moved sufficiently toward the left (still referring to Fig. 2) to open the port or passage E wide the parts or projections B³ of the said valve-head will overlap the reduced 75 portion B⁵ of the bottom of the steam-chest, and thus allow the steam to pass beneath the said projections, rendering them neutral or functionless under the conditions named.

The lower packing-plate part B¹⁰ on each 80 side of each valve-head is supported upon a pin B¹², made fast in the head. This plate is allowed to move outwardly freely on the pin, whose only function is to hold the lower extremity of the plate flush with the correspond- 85 ing extremity of the valve-head.

Having thus described my invention, what I claim is—

The combination of a steam-chest whose bottom is curved to conform to the curve of the 90 wall of the cylinder, vertical ports connecting the opposite extremities of the cylinder with the opposite extremities of the steam-chest, and a slide-valve located in the steam-chest and composed of two separated heads, a 95 suitable rigid connection between these heads, and inwardly-projecting parts connected with the heads, the bottom of the steam-chest being provided with seats for these projections while the valve-heads are passing the ports 100 moving inwardly, the bottom of the valve-chest being cut away, to allow the steam to pass underneath the said projections as soon as the heads have opened the steam-ports wide at their inward travel.

In testimony whereof I affix my signature in presence of two witnesses.

LAFAYETTE M. PETTIT.
